UNITED STATES PATENT OFFICE

169,565

CORN POPPER

Emil E. Sivacek, Ann Arbor, Mich., assignor to
King-Seeley Corporation, Ann Arbor, Mich., a
corporation of Michigan

Application June 11, 1951, Serial No. 15,492

Term of patent 14 years

(Cl. D81—10)

To all whom it may concern:

Be it known that I, Emil E. Sivacek, a citizen of the United States of America, residing in the city of Ann Arbor, in the county of Washtenaw, State of Michigan, have invented a new, original, and ornamental Design for a Corn Popper, of which the following is a specification, reference being had to the accompanying drawing, forming a part thereof, wherein:

Figure 1 is a perspective view of a corn popper embodying my new design;

Figure 2 is an exploded view of the corn popper;

Figure 3 is a top plan view thereof; and

Figure 4 is an elevational view thereof in closed position on a slightly reduced scale.

The essential features of my design reside in that portion of the design illustrated in solid lines.

I claim:

The ornamental design for a corn popper, as shown and described.

EMIL E. SIVACEK.
